[57] **CLAIM**

The ornamental design for a combined checking account check and checkbook order recording portfolio, as shown and described.

DESCRIPTION

FIG. 1 is a perspective view of a combined checking account check and checkbook order recording portfolio, showing our new design in a partially open condition;

FIG. 2 is a top plan view thereof;

FIG. 3 is a bottom plan view thereof;

FIG. 4 is an enlarged scale rear elevational view thereof;

FIG. 5 is an edge view of the left panel;

FIG. 6 is an edge view of the right panel;

FIG. 7 is an enlarged scale perspective view of FIG. 1 in the folded closed condition; and

FIG. 8 is a rear perspective view thereof.

*Fig. 1**Fig. 2*
